UNITED STATES PATENT OFFICE.

PETER BROADBOOKS, OF BATAVIA, NEW YORK.

ARCH-SUPPORT.

1,196,205.

Specification of Letters Patent. Patented Aug. 29, 1916.

Application filed October 15, 1915. Serial No. 55,992.

To all whom it may concern:

Be it known that I, PETER BROADBOOKS, a citizen of the United States, residing at Batavia, in the county of Genesee and State 5 of New York, have invented certain new and useful Improvements in Arch-Supports; and I hereby declare that the following is a full, clear, and exact description thereof, reference being had to the accompanying drawings, which form part of this 10 specification.

This invention is a novel arch support for shoes and its object is to provide a support which can be attached to the shoe without 15 injury to the heel thereof, and which can be readily and securely attached to the shank of a shoe in front of the heel.

The novel arch support will not injure the shoe to which the support is attached; 20 and will provide an efficient bearing or support for the arch of the shoe. The support may be provided with a detachable standard which can be changed to suit the height of the heel or arch of the shoe; and such 25 standards are provided with elastic buffers and a metal plate or cap that will prevent wear on the buffer and also protect the standard and buffer from injury by contact with objects on the surfaces upon which 30 the wearer may walk or stand. By reason of the peculiar construction of my arch supports both right and left-shoes can be provided with an arch support suitable to the need and comfort of the wearer.

35 I will explain the invention in detail with reference to the accompanying drawings in which:—

Figure 1 is a side view of a shoe having one of my improved arch supports attached 40 thereto. Fig. 2 is an enlarged bottom perspective view of such a shoe showing the support attached thereto. Fig. 3 is a vertical sectional view through the support as attached to a shoe. Fig. 4 illustrates a 45 slight modification of the support. Fig. 5 is a detail sectional view also illustrating a slight modification of the support. Fig. 6 illustrates a slight modification of the cushion 50 and wear plate.

The support as shown in Fig. 3 comprises 55 a base plate 1 and a tubular standard 2. Said base plate may be parti-circular in contour and is preferably formed with a central opening, and thickened around the edge 60 of said opening as at 1¹, and the opening is internally threaded, as shown in Fig. 3,

for engagement with the upper end of the standard 2 which is preferably externally threaded to engage said opening.

The base plate 1 has a large and substantial bearing on the instep of the shoe and can be readily and securely attached to either new or worn shoes; and the base plate 1 may be secured to the shank of the shoe by means of any suitable fastenings, screws 65 1¹ being indicated in the drawings, and the standard projects downwardly from the base plate at about the center of the shoe shank and in front of the heel so that the standard will stand somewhat inclined to 70 the base plate, but perpendicular to the surface on which the shoe rests.

Within the standard 2 is a resilient cushion 3 formed of rubber or other suitable material, which cushion projects out of and below the standard. The lower face of this cushion is preferably protected by a metal wear plate 4 which may be secured thereto in any suitable way, a screw 5 being indicated in Figs. 1-3. The edge of the plate 4 is preferably flanged as at 4¹ to protect the lower end of the cushion 2 from wear, and increase the hold of the plate upon the cushion. If desired the surface of the plate 4 may be corrugated or roughened as indicated at 4² in the drawings, to cause it to more positively bite the ground or surface upon which the shoe rests and prevent the support slipping. The screw, 5 not only secures the plate 4 to the cushion but forcibly 85 expands the cushion in the standard 2 so that it will be securely fastened thereto.

The wear plate 4 may be permanently attached to the outer end of the cushion if desired in any suitable way, as indicated in 90 Fig. 6. For instance it could be coated with a solution of sulfite of copper and placed in the end of the mold in which the rubber cushion is formed or cast prior to vulcanizing it.

As indicated in Fig. 5 the standard might be cupped or closed at its inner end so that the cushion 3 bears directly against the inner closed end of the standard. The standard 2 may be corrugated or threaded, if 105 desired, as indicated at 2¹ in Fig. 4 so that the cushion will hold firmly therein and not be liable to slip therefrom. The threads or corrugations 2¹ in the standard may be rolled or pressed in the metal. The standards may be formed integral with the base 110 if desired but by having them made sepa-

rately and attachable to the base sets of standards of different lengths can be made, and a standard of the desired length attached to the base, according to the height 5 of the arch or heel of the shoe to which the support is attached and the amount of weight or pressure it is desired to have the support bear when in use.

My arch supports are adapted to the right 10 and the left shoes, and are attached thereto, independently of the heels, and may be placed in exact position to provide the proper and necessary bearing to the instep of the shoe, for either and both the right 15 and the left foot.

What I claim is:

1. An arch support for shoes having a base plate adapted to be attached to the arch of the shoe in front of the heel, a hollow 20 standard depending from said plate and a cushion within said standard adapted to provide a proper instep support, and means for expanding the cushion within the barrel to receive it therein, substantially as 25 specified.

2. An arch support for shoes having a base plate adapted to be attached to the arch of the shoe in front of the heel, a hollow 30 standard depending from said plate, a cushion within said standard adapted to provide a proper instep support; and a screw entering the cushion and expanding same in the standard, substantially as specified.

3. An arch support for shoes having a 35 parti-circular base plate and cylindrical standard or barrel detachably connected therewith, and a cushion within said standard or barrel adapted to provide a proper instep support, and means for expanding 40 the cushion within the barrel to receive it therein.

4. An arch support for shoes having a parti-circular base and a standard, an elastic cushion in the standard, a wear plate on the outer end of the cushion for preserving the same and acting as a foundation plate to take up the wear the support is subjected to, and a screw expanding the cushion in the standard and securing the wear plate to the cushion, substantially as specified. 45

5. An arch support for shoes having a base plate adapted to be attached to the shank of the shoe in front of the heel, a hollow standard depending from said plate, a rubber cushion within said standard and projecting therefrom adapted to provide a proper instep support, a cap on the outer end of said cushion, and a screw expanding the cushion in the standard and securing the cap to the cushion, substantially as specified. 50

6. An arch support for shoes having a base plate adapted to be attached to the shank of the shoe in front of the heel, a hollow standard depending from said plate 55 and standing at an inclined position thereto, a cushion within said standard and projecting therefrom adapted to provide a proper instep support, a metallic wear plate protecting the outer end of the cushion, and a screw securing the cushion in the standard 60 by expanding it therein and also securing the cap to the cushion, substantially as described.

In testimony that I claim the foregoing 75 as my own, I affix my signature in presence of two witnesses.

PETER BROADBOOKS.
